UNITED STATES PATENT OFFICE.

JAMES DENVER, OF NEW HAVEN, CONNECTICUT.

CAR-SEAT ARM.

SPECIFICATION forming part of Letters Patent No. 334,756, dated January 26, 1886.

Application filed April 18, 1884. Serial No. 128,350. (No model.)

To all whom it may concern:

Be it known that I, JAMES DENVER, of New Haven, in the county of New Haven and State of Connecticut, have invented a new Improvement in Car-Seat Arms; and I do hereby declare the following, when taken in connection with accompanying drawings, and the letters of reference marked thereon, to be a full, clear, and exact description of the same, 10 and which said drawings constitute a part this specification, and represent, in—

Figure 1, a perspective view of the cap complete; Fig. 2, a longitudinal central section of the same; Fig. 3, a perspective view of the 15 metal portion of the cap, the non metallic portion removed; Fig. 4, a modification.

This invention relates to an improvement in the arm or cap for car-seat frames. These arms or caps have been made so as to present a 20 complete metal surface, and have also been upholstered so as to present a complete cushioned surface. The complete cushioned surface is undesirable, as it quickly wears. The metal, while overcoming the objections to an 25 upholstered arm, is cold and uncomfortable to the occupant of the seat.

The object of my invention is to construct a seat-arm which, while having all the advantages of the metal arms as to durability and 30 convenience of attachment, may yet avoid the cold metal surface; and it consists in a metallic cap constructed for attachment to the seat-frame and having a non-metallic plate applied at its central portion, shorter than the 35 length of the cap, and so as to leave the metal surface of the cap exposed at each end of the said non-metallic portion, as more fully hereinafter described.

A represents a metal cap constructed to set 40 onto the seat-frame, and so as to be secured thereto—say, by bolts α . Its two ends are curved downward so as to give a convenient and tasteful finish to the ends. On the top or face of the arm is a recess, B. This recess 45 preferably extends from where the curve commences near one end, to the corresponding point at the other, as seen in Fig. 3, but so as to leave the finished portion of the cap ex-

posed at each end of the recess. Into this recess a block, C, is fitted, preferably made 50 from wood, but may be of other non-metallic material, or it may be an upholstered block, if preferred. This block is secured from the under side by screws b , or may be otherwise secured, and is best made flush with the ends 55 of the cap, as shown. This construction gives to the arm all the advantages of a complete metal cap without the objection of a metal surface, inasmuch as the non-metallic portion C covers all that portion of the cap upon 60 which the arm of the occupant of the seat would naturally rest, but leaves the metal surface of both ends of the cap exposed beyond the ends of the non-metallic portion, and so that the principal wear upon the cap in passing in and out of the seat comes directly upon 65 the end portions of the cap, and not upon the arm-rest.

While I prefer to form the recess so that the block introduced may stand flush with the 70 two ends, it may be raised above the surface, as seen in Fig. 4.

I claim—

1. The herein-described seat-arm for railway-cars, consisting of the metal cap A, fitted for attachment to the seat-frame, constructed with a recess, B, upon its upper surface shorter than the length of the cap, and so as to leave a portion of the cap at each end of said recess, combined with a non-metallic 80 block, C, secured in said recess, and so as to leave the said end portions of the cap exposed at the respective ends of the said non-metallic block, substantially as described.

2. A seat-arm composed of a metal cap, A, 85 constructed for attachment to the seat-frame, combined with a non-metallic block, C, shorter than the arm, and secured upon the cap and so as to leave the end portions of the cap exposed at the respective ends of the said non-metallic 90 block, substantially as described.

JAMES DENVER.
